UNITED STATES PATENT OFFICE.

GEORGE F. COLBERT AND WILLIAM H. COLBERT, OF PITTSBURGH, PENNSYLVANIA.

COMBINED MIRROR AND TOWEL HOLDER.

Application filed December 16, 1922. Serial No. 607,397.

To all whom it may concern:

Be it known that we, GEORGE F. COLBERT and WILLIAM H. COLBERT, citizens of the United States, and residents of Pittsburgh, in the county of Allegheny and State of Pennsylvania, have invented a new and useful Improvement in Combined Mirrors and Towel Holders; and we do hereby declare the following to be a full, clear, and exact 10 description thereof.

Our invention relates to mirrors and towel holders for use in lavatories, bathrooms, kitchens, and the like, and its object is to provide a simple and inexpensive 15 construction, whereby a mirror and a holder for towels may be combined in a single article.

Another object of our invention is to provide a combined mirror and towel holder 20 which may be conveniently installed in any room without the use of the numerous screws or nails which are necessary in installing mirrors and towel receptacles as ordinarily constructed.

Our improved device includes a frame 25 stamped from sheet metal and of inverted U-shape. A mirror is supported in the upper or closed portion of the frame by means of suitable transverse members, and the projecting lower ends of the frame are utilized as a support for a towel holder 30 consisting of sheet metal end members and a bottom member or bar of glass or other suitable material.

Other novel features of our invention consist in certain details of construction and assembly, these novel details contributing to the inexpensive and simple nature of the device, as will more fully be described below.

In the accompanying drawing, Fig. 1 is a perspective view of a combined mirror and towel holder constructed in accordance with our invention; Fig. 2 is a vertical sectional view of the same device, the section being taken substantially along the line 2—2, Fig. 1; Fig. 3 is a horizontal sectional view, the section being taken substantially on the line 3—3, Fig. 2; Fig. 4 is a partial perspective view of one of the ends of the 45 towel receptacle; Fig. 5 is a fragmentary horizontal sectional view, showing one manner of attaching the towel holder ends to the side rails of the frame, the section being taken substantially on the line 5—5, Fig. 2; Fig. 6 is another fragmentary hori-

zontal section similar to Fig. 5 showing a modified method of attaching the towel holder ends of the supporting frame; Fig. 7 is a side elevational view of the construction shown in Fig. 6, and Fig. 8 is a partial side view showing one construction which may be used when the towel holder is a bar instead of a receptacle.

The drawing shows a three-sided rectangular frame having side rails 2 connected by a top rail 3, the top and sides of the frame being suitably constructed of a single angle bar having each flange cut away at the points of bending, as shown at 4, Fig. 1. A transverse angle bar connects the sides 2 of the frame some distance above their lower ends, and is secured to the sides 2 by means of ears 6 formed at the ends of the bar 5 and attached to the side flanges 7 of the rails 2 by means of screws or rivets 8. The lower ends of the side rails 2 may be connected by means of another angle bar 9 which, like the bar 5, is provided with ears 10 that are attached to the side rails 2 by means of screws or rivets 11, as best shown on Fig. 2. This bar 9 may have one or more openings for admitting screws or nails to assist in fastening the device to a wall or the like.

A rectangular mirror 12 is inserted in the frame formed by the side rails 2, the top rail 3 and the cross bar 5. As shown, the mirror 12 is fastened in this frame by means of a transverse strip 13 having ears 14 formed at its ends and attached to the side rails 2, suitably by means of screws 15. The mirror 12 may have a suitable backing 16 of paper, cloth or other material.

The portions of the side rails 2 projecting below the mirror 12 are employed to support a towel holder consisting of sheet metal side pieces 20 and a bottom 21 which may consist of glass or other desired material. Each of the side pieces 20 is composed of a single piece of sheet metal and has a front flange 22, a rear flange 23, and a socket portion formed at its lower edge for receiving one end of the bottom plate 21.

The rear flange 23 of each of the side pieces 20 is provided with integral ears 25 having openings 26. Screws 27 and nuts 28 may be employed, as best shown in Fig. 5, for attaching the ears 25 to the side rails 2 of the main frame.

Another method of securing the ears 25 to the side rails 2, is shown in Figs. 6 and 7,

- The ears 25 in this case are formed with projections 30 extending inwardly and downwardly and passing through slits formed in the side rails 2, as best shown on Fig. 6. This construction has the advantage that the towel holder may be more readily detached from the side rails 2 than in the construction where the screws 27 are employed.
- 10 Each of the socket members which, as stated above, are formed integral with the end piece 20 of the towel holder, consists of upper and lower horizontal portions 31 and 32 connected by a vertical portion 33 and forming a box-like construction which fits over the end of the bottom plate 21. The front of each of these socket members may be closed by means of an ear 34 formed integral with the upper portion 31 and bent down across the edge of the bottom plate 21.
- 15 Perforated ears 35 may be secured to the top rail 3 for suspending the device from hooks, nails or picture cords, as may be desired or the device may be set upon a shelf or a bracket, the towel cabinet serving as a base and support for the mirror.
- 20 Fig. 1 of the drawing shows the general appearance of the device when in use, the towel receptacle being partly filled with folded paper towels, as shown at 36. A towel holder consisting of a bar of glass or the like, may be substituted for the receptacle, in which case the side members 20 may be modified in the manner shown at 20^a

in Fig. 8 with openings 37 for receiving the ends of a bar 37^a. Holders 38 may be formed integral with the side pieces 20^a for supporting a shelf 39 of glass or other suitable material.

The mirror 12 may be oval, circular, or of any other desired shape, the frame being correspondingly modified. Other details of construction may be varied in many respects without departing from our invention, the scope of which is contained in the appended claims.

We claim as our invention:

1. A structure comprising a mirror, a frame of inverted U-shape surrounding and supporting said mirror and having its leg portions extending beyond said mirror, and a bar connecting said legs above their lower ends and serving as a support for the mirror.

2. A structure comprising a mirror, a frame of inverted U-shape surrounding and supporting said mirror and having its leg portions extending beyond said mirror, a bar connecting said legs above their lower ends and serving as a support for the mirror, and means adjacent to the lower ends of said leg portions for supporting a towel holder.

In testimony whereof we the said GEORGE F. COLBERT and WILLIAM H. COLBERT have hereunto set our hands.

GEORGE F. COLBERT.
WILLIAM H. COLBERT.
